UNITED STATES PATENT OFFICE.

CYRUS M. WALKER, OF BUTLER, MISSOURI.

UNDERGARMENT.

No. 852,306.

Specification of Letters Patent.

Patented April 30, 1907.

Application filed August 2, 1906. Serial No. 328,935.

To all whom it may concern:

Be it known that I, CYRUS M. WALKER, a citizen of the United States, residing at Butler, in the county of Bates and State of Missouri, have invented new and useful Improvements in Undergarments, of which the following is a specification.

This invention relates to undergarments of that class termed union suits and aims to provide a cloth union suit in a manner as hereinafter more specifically described embodying all the advantages and freedom of a knit union suit, furthermore being decidedly more cooler when worn than a knit garment as well as not sticking to the body when the body is wet with perspiration.

The invention further aims to provide a cloth union suit having an elastic waist band of knit fabric constituting the elastic waist portion, thereby preventing any inconvenience to the wearer when using the suit as the wearer will have the utmost freedom, and furthermore, to provide the suit at the shoulder portion thereof with an elastic insert of knit fabric so that the shoulder portion of the garment will not bind the wearer when the suit is worn.

The invention further aims to provide a union suit which shall be simple in its arrangement, strong, durable, and comparatively inexpensive to manufacture.

With the foregoing and other objects in view the invention consists of the novel combination and arrangement of parts constituting the suit as hereinafter more specifically described and illustrated in the accompanying drawings, wherein is shown the preferred embodiment of the invention, but it is to be understood that changes, variations and modifications can be resorted to which come within the scope of the claims hereunto appended.

In describing the invention in detail reference is had to the accompanying drawings wherein like reference characters denote corresponding parts throughout the several views and in—

Figure 1, is a front view of a union suit in accordance with the invention, and—Fig. 2, is a rear view.

A union suit in accordance with the invention comprises a cloth shirt portion 1, and cloth drawers portion 2. The shirt portion being armless and provided with the arm pits 3, and the shirt portion 1, is open in the front and the drawers 2, is open in the front,

the opening extending upwardly from the crotch 4. The drawers portion 2 is also open at the rear, the opening extending from the crotch 4 to a point in close proximity to the waist, and the drawers portion 2 is provided at the rear with a flap 5 for overlapping the rear opening of the drawers portion 2. The legs of the drawers portion 2 are indicated by the reference character 6, and as shown are half or knee length, but the legs 6 may be ankle length if desired. Although the shirt portion 1 is shown armless, yet arms of half or full length may be secured to the shirt portion 1.

The shirt portion 1 is connected to the drawers portion 2 by means of a pair of reinforcing strips 7, 8 which extend from the crotch 4 of the drawers portion 2 to the neck opening of the shirt portion. The reinforcing strips 7, 8 are secured, respectively, to one side of the front opening of the shirt and drawers portion of the garment. Interposed between and secured respectively to the lower end of the shirt portion 1 and the upper end of the drawers portion 2 by suitable stitching is an elastic waist band 9 formed of knit fabric and which extends from the inner side of the reinforcing strip 7 to the inner side of the reinforcing strip 8. The band 9 is of greater width at the back than at the front and allows for perfect freedom of the wearer at the waist and prevents the garment sticking to the body when the body is wet with perspiration. The waist band 9 also constitutes an elastic coupling means between the shirt portion 1 and drawers portion 2. The shoulders of the shirt portion 1 are each formed with an elastic insert 10 of knit fabric which extends from the neck opening to the opening for the arm and gradually increases in width inwardly, this elastic insert affords perfect freedom to the wearer and at the same time also prevents the shoulders of the shirt portion 1 of sticking when the wearer is perspiring.

From the foregoing description, taken in connection with the accompanying drawings, it will be evident that a union suit is set up embodying the advantage of preventing the garment from sticking and at the same time affording perfect freedom to the wearer at the shoulders and waist, and furthermore, the elastic waist band will allow a garment of this character to fit the varying trunks of people of a given chest measure, then again owing to the connecting of the strips 7 and 8

together at the crotch it enables the wearer to get into the garment without putting each leg on like a stocking which has to be done in a knit union suit.

5 Having thus fully described my invention what I claim as new and desire to secure by Letters-Patent, is—

A union garment comprising a shirt portion open at its front, a drawers portion open at its front and rear and having as an integral part thereof a flap for overlapping the opening at the rear, a pair of reinforcing strips for the sides of the front opening of the garment and which extend from the crotch of the drawers portion to the neck opening in the shirt portion, an elastic waist band interposed between the shirt and drawer portion and having its upper edge secured to the lower edge of the shirt portion and its lower edge

secured to the upper edge of the drawer portion thereby coupling said portions together, said band having one end secured to one of the reinforcing strips and its other end to the other of said strips, said band being of greater width at the back of the garment than at the front, and an elastic insert for each of the shoulders of the shirt portion, said insert extending from the neck opening to the opening of the arm and gradually increasing in width toward the neck opening.

In testimony whereof I have hereunto set my hand in presence of two subscribing witnesses.

CYRUS M. WALKER.
